United States Patent Office.

CHARLES G. SARGENT, OF GRANITEVILLE, MASSACHUSETTS.

Letters Patent No. 84,968, dated December 15, 1868

IMPROVED BELT-HOOK

The Schedule referred to in these Letters Patent and making part of the same.

To all whom it may concern:

Be it known that I, CHARLES G. SARGENT, of Graniteville, in the county of Middlesex, and State of Massachusetts, have invented certain new and useful Improvements in Belt-Hooks or Belt-Connections, of which the following is a full, clear, and exact description, reference being had to the accompanying drawings, making part of this specification, in which—

Figure 1 represents a portion of a machine-belt, with my improvements applied to the outside thereof;

Figure 2, an edge view; and

Figure 3, a longitudinal sectional elevation.

Figures 4 and 5 are inner side elevations of my belt-connections detached;

Figures 6 and 7 are end elevations of figs. 4 and 5; and

Figures 8 and 9 are edge views of the same.

Figure 10 represents a double-belt connection, made according to my improvement, that is, having two rows of connecting points for each end of the belt.

This invention relates to a new and improved device for connecting the ends of machine-belts; and

It consists in a novel construction of the implement, and in the peculiar method of forming the connecting-points, which pass through the substance of the belt and hold the ends together.

The object of this invention is to furnish a simple and very efficient belt-connection, which can be easily applied, and so cheap that a new one can be afforded whenever the shortening or other alteration of the belt requires the removal of the implement.

In my said invention, the connecting-points *c* are formed by punching or cutting them from the sheet-metal of which the implement is made, two sides only of each point being cut or punched through the plate, and each point bent round or outward to a right angle with the surface of the plate. Each of the points may be thus bent by or in the punching-operation, the punch being bevelled from the point back to the heel, and a straight back to pass through the opening, and thus bend each point round to the desired position.

These connecting-points may be pointed or bevelled on one or both of their-sides, as shown in figs. 2, 3, 6, and 7, or they may be driven through the substance of the belt, as they are when first formed, but in either case such points should be well clinched on or upon the substance of the belt, so as to prevent the possibility of their drawing out when the belt moves rapidly over a pulley rotating at a high velocity, whereas, if the points were not clinched, the swift motion and centrifugal action would be liable to dislodge the connecting-device, liberate one or both ends of the belt, and do great injury.

Care should be observed, in punching or forming the connecting-points *c*, to punch or cut them in the direc-

tion of the grain of the metal, that is, lengthwise with the grain or fibres of the metal, which are drawn or elongated in the process of rolling, as rolled metal is much tougher and stronger lengthwise than crosswise, and the points thus formed will be very strong and tough, and will not break in bending, the lengthwise direction of the grain or fibres being in the direction of or parallel with the length of the belt, when applied as shown in fig. 1.

Where more than ordinary strain comes on a wide belt, a longer plate may be employed, with two or more rows of points to connect with each end of the belt, as shown in fig. 10, but for all ordinary belts, I find that one row of points passing through the belt, and well clinched, will hold to break or tear strong leather.

If made of good, tough metal, and the points punched in the right direction, as clearly described, these belt-connections may be several times attached and detached by clinching and unclutching the tough points, which will bend easily several times without breaking; but, in order to save time, unless quite at leisure, I generally cut the belt close to the edges of the connection, and then drive in a new one, which costs much less than the time required to remove the simplest belt-connection I have ever seen before.

The connecting-points *c* may be cut or punched, and bent round from the two edges, as shown in the plate *H*, in figs. 1, 2, 3, 4, 6, and 8, or such points may be formed by punching them from the substance of the metal, at a suitable distance from the edges, as shown in the plate *k*, in figs. 1, 2, 3, 5, 7, 9, and 10, but I prefer the latter, as the overlapping edges of the plate beyond the points are drawn closely on to the outside of the belt when the points are clinched down, and their holding-action is thus materially increased.

I do not claim a belt-connection made of cast-metal, points cast in one with the cast plate, such points being set at an angle, to be driven into the belt; nor do I claim metal hooks or studs for connecting the ends of belts, or for attaching straps or loops to boot-tops, such devices being old and well known; but

What I do claim, and desire to secure by Letters Patent, is—

A belt-fastener, consisting of a single strip or piece of sheet-metal, *H* or *K*, having a series of V-shaped hooks, *c*, punched through and out of it, or cut on its ends, with spaces between, and all bent at right angles with it, in the same direction, for the purpose of being passed through the adjoining ends of the belt, and clasped on their under sides, as herein shown and described.

CHAS. G. SARGENT.
